UNITED STATES PATENT OFFICE.

WILLIAM LEARY, OF NEW BEDFORD, MASSACHUSETTS.

COMBINED PARALLEL ROCKER AND PICKING-STICK CHECK FOR LOOMS.

No. 852,515.

Specification of Letters Patent.

Patented May 7, 1907.

Application filed January 11, 1907. Serial No. 351,788.

To all whom it may concern:

Be it known that I, WILLIAM LEARY, a citizen of the United States, residing in New Bedford, in the county of Bristol and State 5 of Massachusetts, have invented a new and Improved Combined Parallel Rocker and Picking-Stick Check for Looms, of which the following is a specification.

This invention has for its principal objects, 10 to transfer the strain of the picking motion from the bolt (which is often broken thereby) to the casting, the picking-stick in the present invention standing on the casting and being supported at its edges and one side 15 by said casting, the bolt being employed solely to retain it in position; to do away with the usual spring and strap on the bottom part of the rocker, which often breaks; to lessen the number of parts and provide 20 greater simplicity of construction; to apply a check at the lower end of the stick which will operate on the stick after the power has been fully delivered and during the further travel of the stick due to momentum, such travel 25 being about three inches in addition to the about nine inches of travel during the delivery or application of the power, thus practically nearly stopping the stick before it reaches the bunter and prevents breakage of 30 the picking-stick; to cushion the pin in the slot in the upper part of the rocker; and in other respects to improve the mechanism and lessen the danger of "smashes" in the shed.

35 The nature of the invention is fully described in detail below, and illustrated in the accompanying drawings, in which:—

Figure 1 is an elevation showing my invention or improvement and the parts of the 40 loom which are directly connected therewith. Figs. 2 and 3 are enlarged sectional details illustrating the rocker in different positions. Fig. 4 is a section taken on line 4—4, Fig. 2. Fig. 5 is a section taken on line 5—5, Fig. 3.

45 *a* represents a portion of the frame of a loom, *b*, a portion of the lay, *c*, *c'* *c''*, the pick-ball and cam-shaft, all constructed as usual—and *d'*, the strap connecting with the picking-stick *d*.

50 Instead of bolting the lower end of the picking-stick to and with its edge against the casting, the bolt extending through it the larger way, whereby practically all the strain of the picking-motion is sustained by the 55 bolt, which frequently breaks, causing "smashes" in the shed of the loom—in the

present invention the lower end of the stick stands on the upper part or member *g* of the parallel rocker, and said member is provided with an upward integral extension consisting 60 of the side portion *h* and parallel end-portions *h'* which are of shape to extend up next one of the sides and both of the edges of the picking-stick, as indicated by broken lines in Figs. 2 and 3, and by full lines in Figs. 4 and 5. A 65 bolt *f* extends horizontally through the part *h* and the stick from side to side, and is secured by suitable nuts *f'*. The bolt simply holds the stick in place, but does not sustain the strain of the picking-motion, such strain 70 being sustained by the parts *h' h* of the casting constituting the upper member *g*. Thus danger of "smashes" from breakage of the bolt is obviated.

The upper member *g* is formed up transversely and centrally at *g'*, and this portion *g'* is provided with a horizontal slot *k* upwardly elongated. The upper member rests on the bottom part or member *l* of the rocker, said bottom part being provided with 80 the bored extension *l'* which receives the rocker-shaft *i* to which it may be rigidly connected in any ordinary manner, as by a setscrew. Ears *n* integral with the member *l* extend up therefrom on opposite sides of the 85 upper member *g* which rests on the lower member between said ears, and a case-hardened pin *p* extends from the ears horizontally through the elongated slot *k*, said pin being secured in the ears in any suitable 90 manner. The lower member is furthermore provided with a central hole *r* into which a projection *s* extends from and integral with the upper member. A spring *t* connects the upper part of the upper member beyond the 95 stick with the extreme end of the outer portion of the lower member, and holds the upper member normally with its heel down, as shown. The lower portion of the slot *k* is provided with a cushion *v*.

When the pick of the loom has been delivered the power of the blow causes the stick to travel some nine inches and then ceases, and the stick travels some three inches farther by momentum and strikes hard against 105 the bunter.

In the present invention the construction provides a check at the lower end of the stick, said check operating on the forward movement of the stick when the power has 110 been fully delivered and during the last three inches of movement by momentum.

In Figs. 1, 2 and 4 the parts are in the position assumed before the beginning of the throw, the spring *t* being relaxed, the pin *p* being in the slot *k* at a distance above the cushion *v*, the projection *s* extending toward the left in the hole *r*. When the stick reaches the point at which its further movement is solely by the power of momentum the cushion *v* is brought up against the pin *p* 5 in the slot *k* by the relative movement of the upper member *g*, the spring *t* is expanded, and the projection *s* is swung toward the right in the hole *r*, all as illustrated in Fig. 3. Thus this cushion (which may be of 10 leather or rubber) comes in contact with the pin after the direct power has gone, checking the stick so that it is practically stopped when it reaches the bunter, and preventing breakage. The diagonally placed spiral 15 spring *t* acts in conjunction with the cushion, and also insures the return of the stick. Moreover the check in combination with the parallel rocker operating on the forward movement of the stick prevents the upper member *g* and the stick from jumping. 20

Having thus fully described my invention, what I claim, and desire to secure by Letters-Patent, is:—

1. In a combined parallel rocker and picking-stick check, an upper member provided with a slotted central transversely thickened portion said slot being upwardly elongated, a cushion in the lower end of the slot, a lower member provided centrally with 30 a vertical hole, a projection extending down-

ward from the upper member into said hole, ears extending upward from the lower member on opposite sides of said thickened portion of the upper member, a pin extending from the ears through said slot, and a spring 40 connecting the outer edge of the upper member with the corresponding end of the lower member, substantially as set forth.

2. In a combined parallel rocker and picking-stick check, an upper member provided with a slotted central transversely thickened portion said slot being upwardly elongated, a cushion in the lower end of the slot, a lower member provided centrally with a vertical hole, a projection extending 45 downward from the upper member into said hole, ears extending upward from the lower member on opposite sides of said thickened portion of the upper member, a pin extending from the ears through said slot, an upward extension integral with the upper member and adapted to lie against the edges and one side of the stick as it stands on the upper member, and a spring connecting the upper outer edge of said upward extension with 50 the outer end of the lower member, substantially as set forth.

In testimony whereof I have signed my name to this specification in the presence of two subscribing witnesses.

WILLIAM LEARY.
